UNITED STATES PATENT OFFICE

93,699

DESIGN FOR A ROOTER'S CHEERSTICK

Felix A. Baschon, Richmond, Va.

Application July 28, 1934, Serial No. 52,730

Term of patent 7 years

To all whom it may concern:

Be it known that I, FELIX A. BASCHON, a citizen of the United States, residing at Richmond, in the State of Virginia, have invented a new, original, and ornamental Design for Rooter's Cheerstick, as shown in the accompanying drawing and described in the following specification.

The figure is an elevational view of a rooter's cheerstick, showing my new design.

The tassels or their equivalent are designed to bear college colors and the device whose shape and arrangement constitute the present design is intended to be carried in multiple by the cohorts or supporters of a team with decorative effect.

I claim:

The ornamental design for a rooter's cheerstick as shown and described.

FELIX A. BASCHON.
